Primary Examiner — John Windmuller*Assistant Examiner* — Luqman McNeil(74) *Attorney, Agent, or Firm* — Baker Law Firm(57) **CLAIM**

The ornamental design for roof safety shorts, as shown and described.

DESCRIPTION

FIG. 1 is a front elevation view of my new design for roof safety shorts;

FIG. 2 is a back elevation view thereof;

FIG. 3 is a right side elevation view thereof;

FIG. 4 is a left side elevation view thereof;

FIG. 5 is a first end view thereof;

FIG. 6 is a second end view thereof;

FIG. 7 is an alternate configuration of the new design for roof safety shorts illustrating the expanding waistband with belt; and,

FIG. 8 shows an embodiment thereof with an open pocket. The broken lines are included for the purpose of illustrating environment and form no part of the claimed design.

1 Claim, 8 Drawing Sheets(56)
